Patented Oct. 23, 1900.

J. B. WEIR.

SEAT POST FOR BICYCLES.

(Application filed Sept. 9, 1899.)

(No Model.)

UNITED STATES PATENT OFFICE.

JOHN B. WEIR, OF CHICAGO, ILLINOIS, ASSIGNOR, BY MESNE ASSIGNMENTS,
TO THOMAS A. BANNING, OF SAME PLACE.

SEAT-POST FOR BICYCLES.

SPECIFICATION forming part of Letters Patent No. 660,285, dated October 23, 1900.

Application filed September 9, 1899. Serial No. 729,908. (No model.)

To all whom it may concern:

Be it known that I, JOHN B. WEIR, a citizen of the United States, residing at Chicago, Illinois, have invented certain new and useful 5 Improvements in Seat-Posts for Bicycles, of which the following is a specification.

My invention relates more particularly to that class of seat-posts which are used in connection with bicycles of the safety or rear-driven type, a type of bicycle in which there 10 is a diamond or other frame having what is known as a "pillar-tube," in which the seat-post is insertable, and particularly to the means by which this seat-post is automatically held in position, adjusted, or removed 15 from its position, as will more fully herein-after appear.

The principal object of my invention is to provide a simple, economical, and efficient 20 seat-post for bicycles formed of two wedges, to one of which is pivoted the seat-post lever by which the post is held in position or removed therefrom; and the invention consists 25 in the features, combinations, and details of construction hereinafter described and claimed.

In the accompanying drawings, Figure 1 is a broken elevation of a portion of a bicycle-frame fitted with a seat-post constructed in 30 accordance with my improvements and partly in section. Fig. 2 is a plan view of the same. Fig. 3 is a longitudinal vertical section taken through a modified form of seat-post. Fig. 4 is a plan view of such modified seat-post, and 35 Fig. 5 is a side elevation of the upper end of such modified seat-post.

In the art to which this invention relates it is well known that the seat-post formed of two plano-convex wedges is the best type in the 40 art; and the object of my invention is to improve this type by simplifying its construction, reducing the cost of its manufacture, and providing means for making desired adjustments to compensate for wear, so that 45 the seat-supporting lever can keep at all times a substantially-horizontal plane.

In constructing my improvements and using them in connection with a pillar-tube A of a bicycle-frame I provide a seat-post 50 formed of two wedges, one of which, B, is tapered downwardly—has its large end at the

top—and the other of which, B', is tapered upwardly—has its large end at the bottom—and which preferably form two plano-convex wedges. These parts may be formed of a 55 tube split diagonally, as shown at b, or of two substantially - semicylindrical wedges, which are struck out from appropriate blanks.

To hold the saddle in position and at the same time firmly secure the seat-post in engagement with the pillar-post of a bicycle, a seat-supporting lever is provided and pivoted at c to the downwardly-tapering member. This seat-supporting lever is preferably formed of a tube or rod divided at its pivoted end into two members which encircle the seat-post on the outside. The upwardly-tapering member is provided with a hole, recess, or indentation c' at its back, and the encircling end of the seat-supporting lever is 70 provided with a tooth, lug, or part c² at its end and adapted to be received in the hole, recess, or indentation in the outer face of the upwardly-tapering member. The rearwardly-extending portion C' of the seat-supporting 75 lever serves to hold the two parts of the post together, so that they can be removed from the pillar-tube without falling apart. In assembling or putting the parts together the upwardly-tapering member is adjusted in the 80 encircling ring of the rearwardly-extending portion of the seat-post lever, so that its tooth, lug, or part is received in the hole, recess, or indentation. The downwardly-tapering member is then adjusted in position and 85 the pin inserted in place, which prevents the upwardly-tapering member from falling out or being removed until the parts have been disassociated by the removal of the pin on which the seat-supporting lever is pivoted. 90 The encircling ring of the seat-supporting lever is made sufficiently loose to permit the desired amount of longitudinal movement in the two parts of the seat-post, so that their engagement or disengagement with the pillar-tube of the bicycle can be readily effected. 95 When the parts are assembled together and inserted in the pillar-tube of a bicycle, engagement with such tube is effected by bearing down on the saddle, which causes the two parts of the seat-post to move longitudinally in that direction, which increases their

diameter. When it is desired to remove the saddle, all that is necessary is to lift up on the seat-supporting lever, when the parts of the post will be moved in that direction, 5 which diminishes the diameter of the post, so that it can readily be removed from the pillar-tube.

In Figs. 3, 4, and 5 I have shown a somewhat-modified form of seat-post, although 10 the principle on which it is constructed is the same as that already described. In this modified form I flatten the upper ends of the wedge portions of the post and flatten the rearwardly-extending portion of the seat-supporting lever, so that the upper end of the post and the encircling ring of the rearwardly-extending portion of the lever will be narrow in cross-section, as will be readily understood from an inspection of Fig. 4. This 15 causes the hole, recess, or indentation *c* in the outer face of the upwardly-tapering member to assume the form of a notch, as will be particularly understood from an inspection of Fig. 3. The tooth, lug, or part *c*² at the 20 end of the rearwardly-extending portion of the seat-supporting lever will also in the modified form simply be a cross-piece uniting the two sides of the encircling end of the seat-supporting lever *c'* in the rear of the 25 upwardly-extending member of the seat-post. By giving the inner face of the ends a turn or rounded conformation, as shown in Figs. 3 and 4, the parts may be disassociated without removing the pin *c*. All that is necessary in this form is to move the parts of the 30 post away from each other at the lower ends, when the upper end of the upwardly-tapering member will turn out of engagement with the piece or pin *c*². If this rounding or turning 35 be omitted, however, the two parts can only be disassociated by removing the pin *c*, as in the form shown in Fig. 1.

By giving the seat-supporting lever a slight incline up or down with reference to the horizontal the rider will be enabled to adjust the 40 angle that he prefers his saddle to keep in riding. As shown in Fig. 3, the seat-supporting lever inclines upward from the horizontal, as shown by the dotted line. This position 45 may be preferred by some riders. If,

however, a rider prefers, he can give the lever an incline downward from the horizontal, as shown by dotted line in Fig. 5, by simply removing the pin *c* and turning the seat-supporting lever over, thus reversing the position of its upper and lower sides. The lever will then incline downward instead of upward from the horizontal. Of course the incline imparted to the seat-supporting lever 55 may be varied according to the preference of the manufacturer or user.

What I regard as new, and desire to secure by Letters Patent, is—

1. In a seat-post for bicycles, the combination of two tapering members forming wedges, 60 and a seat-supporting lever having a slotted head pivotally mounted on one member of the post and exteriorly encircling the upper end of both members with its outer cross end entered into the outer face of the wall of the 65 other member of the post, substantially as described.

2. In a seat-post for bicycles, the combination of two tapering members forming wedges, 70 a seat-supporting lever having a rearwardly-extending portion encircling the post, pivotally secured to one member and provided with a part entering a recess in the outer face of the other member, the inner faces at the upper ends of the two members being sufficiently separated to permit the assembling and disassembling of two of the parts while the seat-supporting lever is pivotally secured in place, substantially as described.

3. In a seat-post for bicycles, the combination of two tapering members forming wedges, 75 and a seat-supporting lever having a rearwardly-extending portion encircling the post and open at top and bottom and pivotally secured by a removable pin to one member and 80 engaging the outer face of the other member and being inclined with reference to a horizontal plane so that it is reversible to change the inclination from the horizontal plane, substantially as described.

JOHN B. WEIR.
